UNITED STATES PATENT OFFICE.

DANIEL APPEL, OF CLEVELAND HEIGHTS, OHIO.

INTERNAL-COMBUSTION ENGINE.

1,311,944.

Specification of Letters Patent.

Patented Aug. 5, 1919.

Application filed March 10, 1916. Serial No. 83,283.

To all whom it may concern:

Be it known that I, DANIEL APPEL, a citizen of the United States, residing at Cleveland Heights village, in the county of 5 Cuyahoga and State of Ohio, have invented a certain new and useful Improvement in Internal-Combustion Engines, of which the following is a full, clear, and exact description, reference being had to the accompanying 10 drawings.

My invention relates to improvements in internal combustion engines of the two-cycle type, and the object of my invention is to eliminate the use of the crank case as a 15 pump chamber, to avoid leakage of the new charge through the crank shaft journals, and my improvement consists in employing the lower end of the cylinder and piston as a supply pump for the new charge by dividing 20 the lower part of the cylinder into two substantially semi-cylindrical pump chambers with a vertically extending slot between the chambers to provide operative movement of the connecting rod between the piston and 25 crank shaft.

My improved engine, which is preferably of the vertical three-port type, is hereinafter more fully described in connection with the accompanying drawings, which form a part 30 of the specification. The same letters of reference indicate corresponding parts in the several views.

In the drawings, Figure 1 is a vertical central section of an engine embodying my 35 invention, this section being in the plane in which the connecting rod operates; Fig. 2 is a vertical central section in a plane at right angles to Fig. 1, looking toward the left hand side of that figure, and showing the piston in its uppermost position and partially in outside elevation. Fig. 3 is a cross section through the exhaust ports and upper transfer ports, as indicated by the line 3—3 on Fig. 1. Fig. 4 is a cross section through 40 the intake ports and lower transfer ports, as indicated by the line 4—4 on Fig. 1. The remaining figures are details, on a larger scale, of the piston and the partition housing for the connecting rod; Figs. 5 and 6 are 45 central vertical sections at right angles to each other through the piston; Fig. 7 is a transverse cross section, as indicated by the line 7—7 on Fig. 6; Fig. 8 is a transverse

vertical section of the housing; Fig. 9 is an inside elevation at right angles to Fig. 8, 55 of one half of the housing, and Fig. 10 is a plan of the housing.

Referring first to Figs. 1 and 2, 11 indicates the cylinder, 12 the piston, 13 the crank shaft, 14 the connecting rod, pivoted to the 60 piston and the crank, and 15 a stationary tubular housing with a circular base, fitting into the bottom end of the cylinder. As shown the lower end of the engine cylinder is provided with an external flange 21 secured to an annular rim 22 of the crank case 65 20 by the usual means, while the housing 15 is so secured to an inwardly projecting flange 48 of the crank case as to permit it to align with the piston. The crank shaft may 70 be mounted in a two-part casing 20, as shown.

The piston has on its upper surface the usual deflector 31 and near the top the packing rings 32. Below these is a transverse 75 bearing 33 for the wrist pin 34, and below the wrist pin the piston continues for a length slightly more than the stroke of the piston. The lower portion of the piston is divided by a slot 35, diametrically across 80 and at right angles to the wrist pin, and parallel flat walls 36, form the sides of this slot and unite with the circular walls of the piston adjacent to the walls of the cylinder, to form substantially semi-cylindrical down- 85 wardly projecting hollow plungers closed at their upper ends by the wall 37, but communicating with the cylinder space below.

The stationary central partition for enclosing the connecting rod is of the form 90 shown in Figs. 8, 9 and 10, and consists of a circular base 40 with an upwardly extending tubular partition 41, and rising therefrom for a distance slightly greater than the stroke of the piston, the partition and base 95 being composed of two parts and joined vertically adjacent to their edges by inwardly projecting ribs 42, and secured together near the upper ends by screws 45. The housing thus provides a tubular partition which extends diametrically across the cylinder and provides a slot 43 in which the connecting rod can freely operate. It is to be understood that the inner faces of the piston slot 35 and the outer faces 41 of the central partition must be in sliding contact with each 100 105

other, similar to the circular face of the piston with the walls of the cylinder. It is also to be understood that any wear between the flat walls of the partition and piston 5 may be taken up by separating the members of the two-part partitions.

Referring now to the several ports in the cylinder and piston of the engine; these are preferably arranged in pairs near the out- 10 side of the partition walls of the tubular housing and the flat walls of the piston. In Fig. 2 at 50, 50, are shown two intake ports through the lower portion of the cylinder leading from an intake passage 51. 15 52, 52 indicate lower transfer ports opposite the intake ports and leading to a transfer channel 53. This channel is shown on the outside of the cylinder wall, covered by a suitable plate 54. At its upper end the 20 transfer channel communicates with two ports 55 leading into the upper end of the cylinder, and opposite these ports are the exhaust ports 56, 56, communicating with the exhaust port 57. In the piston walls, 25 near the upper end of the semi-cylindrical compression chambers, are two ports 58 adapted to register with the transfer ports 52 when the piston is at the lower end of its stroke, as shown in Fig. 1.

30 It will be seen from Fig. 2 that when the piston is at the upper end of its stroke the intake ports 50 are entirely uncovered, and as the piston moves downward, ports 50, 50 will be closed, than as the piston nears the 35 lower portion of its stroke, first the exhaust ports are uncovered, and then, while the uncovering of these ports continues, the piston ports 58 are coming into registration with the lower transfer ports 52, and immediately thereafter the piston uncovers the 40 upper transfer ports 55. The registration of the ports 58, with the ports 52, is slightly in advance of the uncovering of the ports 55. In the lowermost position of the piston, shown in Fig. 1, both transfer ports 45 and the exhaust ports are fully open.

Assuming that on the up stroke of the piston a partial vacuum is created in the semi-cylindrical pump chambers provided 50 between the lower end of the cylinder and piston, and when the piston uncovers the intake ports 50, combustible mixture is drawn in from the carburetor, and as the piston descends, this combustible mixture is 55 compressed in the pump chambers, and when the ports 58 in the piston reach the lower transfer ports 52 the combustible mixture flows into the transfer passage channel 53 and immediately after the piston uncovers 60 the upper transfer ports 55, and the new charge is forced through these ports into the combustion end of the cylinder. The new charge, on entering the cylinder, is diverted upwardly by the deflector 31, and 65 passes the spark plug 61, and while turning

downward, forces out the burned gases while the exhaust port is being fully uncovered.

My improved engine is shown herewith as a three-port single air-cooled unit, with cooling ribs 60, but it will be understood 70 that my improvements apply equally well to other types of two-cycle engines, and other forms of cooling may be employed, and that the cylinder may be arranged on the crank case in any desirable manner, 75 without departing from the spirit of my invention.

Having thus described my invention, what I claim is:

1. In an internal combustion engine, the 80 combination, with a single-diameter cylinder, a single-diameter piston, a crank and a connecting rod, of a base partition across the cylinder between the piston and crank and having an elongated opening in which 85 the connecting rod swings, and means surrounding the connecting rod and extending between the base partition and piston and extending transversely clear across the cylinder to divide it into two chambers independent of the space in which the connecting rod operates.

2. In an internal combustion engine, the combination of a single-diameter cylinder, a single-diameter piston therein, a crank, a 95 connecting rod pivoted at one end to the piston and at the other end to the crank, a base partition across the cylinder between the piston and crank, and having an elongated opening in which the connecting rod 100 swings, and a tubular member surrounding the connecting rod and extending from the partition to the piston, the piston having a sliding engagement with the exterior of said tubular member, said tubular member extending clear across the cylinder and dividing its interior into two receiving chambers 105 between opposite sides of the tubular member and the cylinder wall respectively.

3. In an engine, the combination of a cylinder, a piston therein having an open-ended transverse slot, a crank, a connecting rod pivoted at one end to the piston and at the other end to the crank and occupying said slot, and means closing the end of the cylinder between the piston and crank and having a tubular member surrounding the connecting rod between said partition and piston and extending into the slot in the piston, there being ports leading to and 115 from the cylinder outside of said tubular member.

4. The combination, with a single-diameter cylinder, a single-diameter piston having an interior space, a crank and a connecting rod, 125 of a housing surrounding the connecting rod and slidably engaged by the piston and having an opening in the top communicating with the interior space of the piston said housing extending clear across the cylinder 130

- and dividing its interior into two receiving chambers between opposite sides of the housing and the cylinder wall respectively.

5. The combination of a cylinder, a piston therein having a transverse slot, and a stationary housing extending into said slot and having sliding connecting with the walls of the slot and surrounding the connecting rod, said housing having a connection adjacent to its lower end with the cylinder wall.

10. The combination of a vertical cylinder, a piston therein having a transverse slot, a connecting rod pivoted to the piston and swinging in said slot as the piston reciprocates, a tubular housing having a circular base extending from the bottom of the cylinder beyond the piston stroke, the piston slot having sliding connection with the sides of said housing, and ports leading to and from the cylinder space outside of said housing.

15. The combination of a cylinder, a piston therein having a transverse slot extending clear through it, a connecting rod pivoted to the piston and swinging in said slot as the piston reciprocates, a flat tubular housing located transversely across the cylinder, the piston having sliding connection with the flat faces of said housing, a transverse partition connecting the end of said housing 20 with the cylinder wall, whereby a chamber is provided between each side of the housing and the cylinder wall, intake ports to such chambers, and transfer ports leading from such chambers.

25. The combination of a cylinder, a piston therein, a wrist pin carried by the piston, a connecting rod on the wrist pin, the piston being continued below the wrist pin and such lower part of the piston having two partitions across it providing a transverse slot in which the connecting rod works, and a chamber on each side of said slot closed at its upper end, a housing in the form of a flattened tube surrounding the connecting 30 rod, the piston having a sliding connection with said housing, a circular base connecting the housing with the cylinder beyond the piston stroke, whereby chambers are provided on opposite sides of the housing communicating with the chambers in the piston, intake ports through the cylinder wall opening directly into the chambers in the cylinder and positioned to be uncovered by the piston, transfer ports through the cylinder 35 wall, and ports through the piston near the upper end of the chambers therein adapted to register with the transfer ports.

40. The combination of a cylinder, a piston therein having a transverse slot, a connecting rod swinging in said slot, a housing consisting of a flattened tube surrounding the connecting rod and forming at each side thereof chambers of substantially equal volume, the slotted piston sliding over said 45 housing, the housing having a circular base

45. The combination of a cylinder, a piston therein having a transverse slot, a connecting rod pivoted to the piston and oscillating and reciprocating in said slot, the piston slot having operative connection with said housing and the housing having a base connected with the cylinder beyond the end of the piston stroke, said housing comprising a pair of laterally separable members connected together to surround the connecting rod.

50. In an internal combustion engine, the combination with a cylinder, of a piston therein having a transverse slot, a connecting rod pivoted to the piston and working in said slot, a base member connected with the cylinder beyond the end of the piston stroke, a tubular housing rising from said base member open at its upper and lower ends and surrounding the connecting rod, the slotted piston having sliding engagement with the outer sides of said tubular member, and said housing and base comprising a pair of separable members secured together and adapted to be separated to compensate for wear.

55. The combination of a cylinder, a piston therein having a transverse slot extending entirely across it, a flattened tubular housing extending transversely across the cylinder and having its opposite edges fitting the cylinder walls and having its sides engaging the slot in the piston, partitions between the end of such tubular housing and the cylinder wall, whereby substantially semi-cylindrical chambers are provided between the flat housing walls and the cylinder wall, ports communicating with said chambers, and a connecting rod pivoted to the piston and operating in the space provided by the slot in the piston and in the interior of the housing.

60. The combination of a cylinder, a crank case carrying the same, a partition extending crosswise of the lower end of the cylinder secured to the crank case and having a transverse slot across it, a transversely located housing carried by said partition comprising a flattened tube extending between opposite sides of the cylinder wall, a piston in the cylinder having a slot in its lower portion which makes a sliding connection with the housing, ports leading to the chambers between the housing wall and cylinder wall, a crank mounted in the crank case, and a connecting rod pivoted at its lower end to said crank and extending through the housing and slot in the piston and operatively connected with the piston.

65. The combination of a cylinder, a piston therein having a transverse slot, a connecting rod swinging in said slot, a housing consisting of a flattened tube surrounding the connecting rod and forming at each side thereof chambers of substantially equal volume, the slotted piston sliding over said housing, the housing having a circular base

14. The combination of a cylinder, a piston therein having a transverse slot with parallel flat walls, a housing comprising a transversely positioned flattened tube extending into said slot, and a circular base connecting the end of said tube with the cylinder wall, said housing being laterally separable on a diametric plane, and a connecting rod pivoted to the piston and swinging in the slot thereof and in the tubular opening in the housing, the housing walls positioned close to the opposite sides of the connecting rod.
15. In a two cycle engine of the three port type, the combination, with a crank case, a crank therein, a cylinder secured to the crank case, a piston in the cylinder having a transverse slot, a connecting rod having a wrist pin connection with the piston at the upper end of said slot and a crank connection at its lower end, a circular partition fitting within the cylinder at the lower end thereof secured to the crank case and having a transverse slot through which the connecting rod extends and in which it may swing, and a housing for the connecting rod within the cylinder comprising flat walls rising from said partition on opposite sides of the slot and extending parallel with the diametric plane in which the connecting rod swings, the piston slot having sliding connection with such walls, abutting ribs connecting the two walls adjacent the cylinder wall at opposite sides thereof and providing an intermediate space permitting operation of the connecting rod.
16. In an internal combustion engine, the combination with a cylinder, of a trunk piston therein, a connecting rod pivoted within the piston, said piston having a pair of transverse walls extending across it parallel to and on opposite sides of the plane in which the connecting rod swings, whereby two hollow spaces are provided within the piston each bounded by one of said partitions and by the adjacent cylindrical surface of the piston, there being ports through the piston wall communicating with said hollow spaces, and a partition transverse of the cylinder having a housing in which the connecting rod operates, the outer faces of said housing having a sliding engagement with the inner faces of the partition walls in the piston.
17. In an internal combustion engine, the combination with a cylinder, a base partition across the cylinder carrying a housing extending from cylinder wall to cylinder wall and thereby dividing the space into two independent chambers, a piston having a slot embracing the opposite sides of the housing, the parts of the piston on opposite sides of the slot working in the two chambers referred to, ports communicating with said chambers and ports through the piston

walls, and a connecting rod pivoted to the piston and adapted to swing in an opening within the housing.

18. The combination of a cylinder, a circular base located within the cylinder adjacent to one end, a housing carried by said base extending into the cylinder, said housing having an open interior adjacent to a diametric plane, a bifurcated piston extending into the chambers on opposite sides of the housing, the housing working with a sliding fit in the slot of the piston, and a connecting rod pivoted to the piston and occupying said slot and extending through the open interior of the housing.

19. In an internal combustion engine, the combination with a cylinder, a piston working therein, there being a single combustion chamber between the piston and the head of the cylinder, two separated extensions on the piston, two chambers in which said extensions operate, ports to and from said chambers, means connecting the exit ports with said combustion chamber, and a connecting rod pivoted to the piston and swinging in a transverse opening between said chambers.

20. In an internal combustion engine, the combination of a cylinder, a piston therein having two extensions on the end of the piston which faces the crank, a pair of compression chambers between the piston and crank in which said extensions operate, intake ports leading into said compression chambers, transfer ports and a transfer passageway to enable communication from the compression chambers to the combustion space between the piston and the head of the cylinder, a crank, and a connecting rod pivoted thereto and to the piston and operating in the space between said piston extensions and between said compression chambers.

21. The combination, with a cylinder, a piston, a crank, and a connecting rod pivoted to the piston and connected with the crank, a pair of separated extensions carried by the piston on the crank-side thereof and on opposite sides of the connecting rod, a pair of pump chambers in which said extensions operate, the inner sides of said pump chambers being defined by a stationary intermediate partition having an opening through it through which the connecting rod extends.

22. In an internal combustion engine, the combination with a cylinder, a piston working therein, there being a combustion chamber between the piston and the head of the cylinder, two extensions of the piston, two chambers within which said extensions operate, two ports for gaseous fluid to and from each of said chambers, means connecting the ports from said chambers with the combustion chamber, and a connecting rod pivoted to the piston swinging between said chambers.

23. In an internal combustion engine, the combination with a cylinder, a piston working therein, there being a single combustion chamber between the piston and the head of the cylinder, two extensions of the piston, two chambers within which said extensions operate, two ports for gaseous fluid to and from each of said chambers, means connecting the ports from said dampers with the combustion chamber, and a connecting rod pivoted to the piston swinging in a transverse opening between said chambers.

24. In an internal combustion engine, the combination with the cylinder, piston, crank chamber, crank and connecting rod, of a partition transversely of the cylinder between the piston and crank, and a housing surrounding the connecting rod and extending between the piston and partition and sliding into one of such members, said housing extending transversely across the cylinder to divide it into two chambers.

25. In an internal combustion engine, the combination of a single diameter cylinder, a single diameter piston therein, a crank chamber adjoining the cylinder, a crank in the

crank chamber, a connecting rod connecting the piston with the crank, a laterally elongated housing extending across the cylinder and surrounding the connecting rod, a partition transverse of the cylinder between it and the crank chamber, said housing extending from the piston to the partition and being rigid with one of such members and slideable in the other, and ports to and from the cylinder spaces on opposite sides of the housing.

26. The combination with a cylinder, a piston, a crank, and a connecting rod, pivoted to the piston and connected with the crank, of a housing about the connecting rod comprising a flattened tube extending across the cylinder and having an internal space in which the connecting rod swings, means for closing the cylinder space on opposite sides of said housing to provide two chambers acted on by said piston, and ports communicating with the chambers last mentioned.

In testimony whereof, I hereunto affix my signature.

DANIEL APPEL.
